UNITED STATES PATENT OFFICE.

BENJAMIN PARDO, OF ALAMEDA, CALIFORNIA.

DESIGN FOR AN INCENSE-BURNER DOLL.

Application filed May 7, 1923. Serial No. 6,092. Term of patent 3½ years.

To all whom it may concern:

Be it known that I, BENJAMIN PARDO, a citizen of the United States of America, and a resident of Alameda, county of Alameda, and State of California, have invented a new, original, and ornamental Design for an Incense-Burner Doll, of which the following is a specification, reference being had to the accompanying drawings, forming part thereof.

In the drawings which illustrate my new design—

I claim:

The ornamental design for an incense burner doll substantially as shown.

BENJAMIN PARDO.
